UNITED STATES PATENT OFFICE.

CALVIN G. UDELL, OF NORTH INDIANAPOLIS, INDIANA.

STEP-LADDER.

SPECIFICATION forming part of Letters Patent No. 254,518, dated March 7, 1882.

Application filed August 15, 1881. (No model.)

To all whom it may concern :

Be it known that I, CALVIN G. UDELL, a citizen of the United States, residing at North Indianapolis, in the county of Marion and State 5 of Indiana, have invented a new and useful Improvement in Step-Ladders, of which the following is a specification.

My invention relates to improvements in step-ladders, in which, first, the braces of the 10 ladder are securely fastened to the legs by clamping-bands, which, while holding the ends of the braces firmly, prevent the ends of said braces from splitting; second, the rear leg of the ladder is supported about midway of its 15 height by a sliding brace-bracket; and, third, the top step is firmly clamped in the hinge-bracket, preventing it from getting loose or splitting; and the object of my invention is to furnish a stronger and more durable step-ladder than heretofore. This object I accomplish by the devices illustrated in the accompanying drawings, in which—

Figure 1 represents a rear elevation of a step-ladder embodying my improvements. Fig. 2 25 is a side elevation of a step-ladder, partially in section. Fig. 3 is a plan view of one of the hinge plates or brackets. Fig. 4 is a modified form of said hinge-bracket. Fig. 5 is a modified form of one end of the hinge-bracket. Fig. 30 6 is an enlarged side and end view of the brace-bands. Fig. 7 is a side and end view of the cross-bar staple band or clamps. Fig. 8 is a view of a band with drawing-spurs, used to clamp the braces and legs together at the sides, 35 and is made fast by a screw which passes through it into the braces and legs. Fig. 9 represents enlarged detail views of the sliding brace. Fig. 10 represents a side view of the clamp-band for holding the cross braces and 40 upright bar for the slide-brace, and Fig. 11 represents a side and end view of the pivot socket for the upper end of the upright bar of the slide-brace to operate in.

Similar letters in the various views refer to 45 like parts.

I represents the step-ladder, and A the rear legs. The upper ends of the rear legs, A A, are provided with the ordinary hinges F, the pivot 50 portion of which operates in the holes X of the hinge plates or brackets P'. The upper step, G, of the ladder is placed over the hinge plates

or brackets P P', and the projecting prongs a are driven into the edges of the step. The pin f on the bar p of the section P', also the

pin f' on the bar p', are then inserted in the 55 holes f' and f' of the section P. Thus the two parts P P' are firmly united, with the step G, clamped fast. The sections P P' are then made fast to the sides of the stiles of the ladder I by screws, as shown in Fig. 2. In Fig. 4 a modified form of the hinge plate or bracket is shown 60 cast in one piece, instead of two, as in Fig. 3.

In Fig. 4 the part P² has the bar p³ and hinge part p⁴ cast on it. The upper bar, p, has a pin, f, at its end, to engage in its hole f' in the part 65 P², and thus hold the upper part of the bracket rigid. Each end of the bracket is provided with spurs a a to drive into the front and rear edges of the top step, G, and hold it fast, the same as shown in Fig. 2. In securing it to the 70 step the pin f is removed from its hole f', and the parts P² and p⁴ spring apart far enough to permit the step G to be inserted between the spurs a a, which are then driven home into the 75 edges of the step until the pin f enters the hole f', where the plate or bracket is made fast to the step-ladder, as before described.

Fig. 5 shows a modified form of the ends of the hinge-plate. Instead of having a spur, it has a lug, p⁵, with a hole, r, in which a nail 80 or screw may be inserted and driven into the edges of the top step, G. The upper and lower ends of the braces B B are secured to the legs A A by the bands b b b b, which clasp the ends of the braces and legs, and are made fast by 85 screws passing through the hole b² in one side of the band into the braces and legs, as shown in Figs. 1, 2, and 6. The draw-clamp, Fig. 8, may be used and the draw-spurs w² forced into the sides of the legs, drawing them and the 90 braces snugly together, where they are made fast by a screw passing through the hole in the part w.

The cross-bar C has its ends secured to the legs A A by the staple-clamps d, which have 95 their ends driven into the legs above and below the brace, and the staple is then secured by a screw or nail passing through it and the brace into the legs, as shown.

One end of the sliding brace J is pivoted to 100 the step M at K. The other end is pivoted at L to the slide H. Said slide H operates on

the vertical bar D, which has its lower end made fast to the braces B B, where they cross, by the band h, Fig. 10, which is constructed to fit the braces and bar and hold the bar firm. The upper end of the bar D is inserted in the socket of the casting E, which is secured to the under side of the upper step, as shown in Figs. 1 and 11.

It is obvious that the upper end of the bar D may be inserted in a socket formed in the step, or its upper end may be pivoted thereto; but I prefer the socket E.

In closing up the ladder the slide H is raised on the bar D, thus permitting the rear legs to fold up against the ladder.

What I claim as new, and desire to secure by Letters Patent, is—

1. In combination with the rear legs, A A, of a step-ladder and the cross-braces B B, the band-fastenings b, substantially as shown and described.

2. In combination with the rear legs, A A, of a step-ladder and the cross-bar C, the staple-fastenings d, substantially as specified.

3. In combination with the rear legs, A A, 25 of a step-ladder, the bar D, with slide H, and the brace J, pivoted to the step M of the ladder and to said slide, substantially as specified.

4. In combination with the step-ladder I, the 30 hinge-bracket P P', or its equivalent, as shown, with spurs a a, fastening-pin f, and hole f', and the top step, G, substantially as shown and described.

5. In a step-ladder, the upright bar D, having its lower end made fast to the cross-braces B B and its upper end pivoted to the top step, G, substantially as specified.

In testimony whereof I have signed my name to this specification in the presence of two sub- 40 scribing witnesses.

CALVIN G. UDELL.
